RAYMOND FOSS BACON AND CLINTON W. CLARK, OF PITTSBURGH, PENNSYLVANIA.

TREATMENT OF PETROLEUM HYDROCARBONS.

1,101,482.

Specification of Letters Patent. Patented June 23, 1914.

Application filed May 6, 1912. Serial No. 695,408.

To all whom it may concern:

Be it known that we, RAYMOND FOSS BACON and CLINTON W. CLARK, both residing at Pittsburgh, in the county of Allegheny and State of Pennsylvania, and both citizens of the United States, have invented or discovered certain new and useful Improvements in the Treatment of Petroleum Hydrocarbons, of which improvements the following is a specification.

Our invention relates to the treatment of petroleum hydro-carbons, and its object is to increase the yield of gasoline from such mineral oils.

Of the gasoline now used for internal combustion engines and like purposes, by far the largest part is obtained by the fractional distillation of crude oil under substantially atmospheric pressure, the cut sold as the best gasoline ranging usually from boiling point of approximately 30° C. to 150° C. The supply thus obtained, has, both because of the increasing demand for gasoline and because of the falling off of the supply of petroleum, proved to be inadequate. Therefore, more specifically stated, the object of our invention is to provide a method for converting into gasoline petroleum hydro-carbons from which the usual gasoline component has already been removed by fractional distillation, or hydrocarbons which do not originally contain gasoline.

We have discovered that such low boiling point hydrocarbons as are used as gasoline may be obtained from hydrocarbons having boiling points above that ordinarily used as gasoline by distilling the high boiling point hydrocarbons under pressure; and further, we have discovered that, within certain approximate limitations of pressure, the yield of gasoline thus obtained will be materially greater than when the distillation is effected under pressures above and below such limitations; and, still further, we have ascertained that, aside from the lower yields of gasoline, the economic conditions of operation are prejudicial when effected both above and below such limitations of pressure. As far as the increase in gasoline yield is concerned, our discovery stated in terms of pressures and boiling point temperatures of the hydrocarbons, is that a mixture of hydrocarbons of boiling points ranging from about 30° to 150° C. at atmospheric pressure, and hereinafter referred to as low boiling point hydrocarbons, may be

obtained in relatively large quantities from hydrocarbons of boiling points of about 250° C. and upward at atmospheric pressure, and hereinafter referred to as high boiling point hydrocarbons, by distilling such high boiling point hydrocarbons at a pressure ranging from about 100 to 300 pounds per square inch, and subsequently distilling by fractional distillation the distillate thus obtained.

Not only are large quantities of low boiling-point hydrocarbon obtained by distilling high boiling-point hydrocarbons at a pressure ranging from about 100 to 300 pounds per square inch, but the quality, also, of the low boiling-point hydrocarbons thus obtained is materially better for commercial purposes than that obtained by distillation at pressures below 100 pounds. That is to say, of the two hydrocarbons, namely, saturated hydrocarbons which are deodorized and desirable commercially and unsaturated hydrocarbons which have the opposite characteristics, the percentage of the former, as compared to the latter, is materially greater when distillation is effected at pressures above 100 pounds than at pressures below it, and is substantially a constant quantity at distillation pressures above about 100 pounds. Consequently, the subsequent refining loss, due to the presence of the unsaturated hydrocarbons, which yield tar by the action of the refining acid, is materially lessened, our practice showing that this loss, which is substantially uniform with gasoline resulting from distillation at 100 pounds pressure and upward, increases rapidly with gasoline resulting from distillation at pressures ranging downwardly from 100 pounds.

It will be understood that in practising the invention, the operator will, in establishing the pressure prevailing within the still within the described range, likewise provide for such rate of distillation as will give at least the minimum proportional yield of low boiling hydrocarbons desired, which yield, for commercial purposes, may be taken at 105 say 18%, by volume, of saturated hydrocarbons.

Other conditions being equal, the rate of distillation will depend upon the temperature, and this is within the control of the operator who will decrease it should the percentage of low boiling point hydrocarbons, at the established high pressure, fall below the optimum.

In determining the approximate lower limit of 100 pounds pressure per square inch we find that, when high boiling point hydrocarbons are distilled at a pressure below 5 about 100 pounds, there is a relatively small yield of low boiling point hydro-carbons as compared with that obtained by distillation at a pressure above 100 pounds, all other conditions being the same. Furthermore, 10 such yields of low boiling point hydro-carbons as may be obtained at a pressure below about 100 pounds are effected only at such sacrifice of time and fuel as to render working at such low pressures uneconomic and 15 impractical. In determining the upper limit of about 300 pounds per square inch, we find that above this distillation pressure there is not only a dropping off of the percentage of obtainable low boiling point 20 hydro-carbons, but that the still becomes coated with coke so rapidly that its heat conductivity is diminished and there is a constant liability of its blowing out. Also, the loss of hydro-carbons through gasification 25 when distilling at pressures above approximately 300 pounds is a prejudicial factor.

The temperature at which our method may be practised depends, of course, upon the character of the high boiling point hydrocarbons treated. The temperature in 30 each instance will be such as to keep the mass, which is being distilled, under a pressure of from about 100 to 300 pounds. As an example of the temperature which may 35 be required we find that a reduced Oklahoma petroleum (such petroleum having had its gasoline and kerosene components removed from it) distils under a pressure of about 200 pounds at a temperature ranging from 40 about 350° to 500° C. In order to obtain the desired low boiling point hydro-carbons from the distillate thus produced, such distillate is subjected to the ordinary fractional 45 distillation at substantially atmospheric pressure, subsequently to the distillation under pressure.

By the complete process as now described we have been able to obtain as much as 42% 50 of gasoline, that is, hydro-carbons boiling at a temperature ranging from about 30° to 150° C. at atmospheric pressure, from hydro-carbons which before being subjected 55 to the treatment of our invention contained no low boiling point hydro-carbons. Such increase in the yield of said low boiling hydro-carbons is not nearly so great when the mass of high boiling point hydro-carbons is first heated for a substantial length 60 of time in a closed still or other receptacle to a pressure between 100 and 300 pounds per square inch, and subsequently distilled at about atmospheric pressure, as when the distillation is effected under the prescribed

limitations of pressure. We do not herein 65 make any attempt to account for this difference in the yield but find that it is a fact.

Any still capable of withstanding the prescribed pressures, namely 300 pounds per square inch may be employed in the practice 70 of our invention. The accompanying drawing, which forms part of our specification, is a view partly in elevation and partly in longitudinal section showing somewhat diagrammatically an apparatus which may be employed in the practice of our invention. 75 The still 1 is connected, as by pipe 6, to a suitable source of oil supply, and has a pipe 7 extending from its upper portion through a condenser 2 to a receptacle 3. A gage for showing the pressure is indicated at 4, and 80 a valve 5 for regulating the pressure is placed at any desired point along the pipe 7. In operation the high boiling point hydrocarbons will preferably be fed continuously to the still 1, and the temperature of the 85 still contents will be suitably regulated to keep the pressure therein between 100 to 300 pounds.

We claim as our invention:

1. The herein-described method of producing saturated gasoline hydrocarbons, (i. e. hydrocarbons having boiling points ranging from about 30° C. to 150° C. at atmospheric pressure), which consists in simultaneously decomposing and distilling, under 95 a pressure ranging from 100 to 300 pounds per square inch, petroleum hydrocarbons having a boiling point of about 250° C. and upward, the operation being conducted at a rate to give a yield of saturated gasoline 100 hydrocarbons of a minimum volume of substantially 18% of the distilling charge.

2. The herein-described method of producing saturated gasoline hydrocarbons, (i. e. hydrocarbons having boiling points 105 ranging from about 30° C. to 150° C. at atmospheric pressure), which consists in simultaneously decomposing and distilling, under a pressure ranging from 100 to 300 pounds per square inch, petroleum hydrocarbons having a boiling point of about 250° C. and upward, the operation being conducted 110 at a rate to give a yield of saturated gasoline hydrocarbons of a minimum volume of substantially 18% of the distilling charge, 115 and subsequently treating the distillate so obtained for the separation of the saturated gasoline hydrocarbons.

In testimony whereof we have hereunto set our hands.

RAYMOND FOSS BACON.
CLINTON W. CLARK.
